(57) CLAIM

The ornamental design for a pen, as shown and described.

DESCRIPTION

FIG. 1 is a perspective view of a pen showing my new design; FIG. 2 is a front elevation view of the pen of FIG. 1; FIG. 3 is a rear elevation view of the pen of FIG. 1; FIG. 4 is a left side elevation view of the pen of FIG. 1; FIG. 5 is a right side elevation view of the pen of FIG. 1; FIG. 6 is a top plan view of the pen of FIG. 1; and, FIG. 7 is a bottom plan view of the pen of FIG. 1. The broken lines in the drawings showing the clip and the writing point in FIGS. 1-7 are included for the purpose of illustrating portions of the pen that form no part of the claimed design.

1 Claim, 4 Drawing Sheets

FIG. 2

FIG. 3

FIG. 4

FIG. 5

FIG. 6

FIG. 7
